UNITED STATES PATENT OFFICE.

ALONZO HAYNES, OF JACKSON, AND JOHN F. MARTIN, OF ALBION,
MICHIGAN; SAID HAYNES ASSIGNOR OF HIS RIGHT TO ALBERT W.
AUSTIN, OF JACKSON, MICHIGAN.

WIRE ARTICLE.

No. 820,716.

Specification of Letters Patent.

Patented May 15, 1906.

Application filed May 1, 1905. Serial No. 268,339.

To all whom it may concern:

Be it known that we, ALONZO HAYNES, residing at Jackson, in the county of Jackson, and JOHN F. MARTIN, residing at Albion, in the county of Calhoun, State of Michigan, citizens of the United States, have invented a new and useful Wire Article, of which the following is a specification.

This invention relates generally to wire articles, and particularly to that class embodying a plurality of pivotally-connected sections or members that by having their positions changed relatively to each other are capable of presenting a variety of designs to adapt the article for numerous uses—such, for instance, as a flower-holder, a fruit-holder, a waste-paper basket, a clothes-hamper, a cake-dish, a teapot-stand, or various other designs too numerous to mention.

The object of the present invention is to combine the parts of the article in such manner as to permit of their being readily adjusted without danger of separation to secure the desired design.

With the above and other objects in view, as will appear as the nature of the invention is better understood, the same consists in the novel construction and combination of parts of a wire article, as will be hereinafter fully described and claimed.

In the accompanying drawings, forming a part of this specification, and in which like characters of reference indicate corresponding parts, Figure 1 is a view in side elevation exhibiting the article adjusted to form a fruit-basket. Figs. 2 and 3 are detail views of the joint employed in connecting the body members.

The article of the present invention in this instance is shown as consisting of three assembling members 1, 2, and 3 and a plurality of body-forming members 4, the assembling members and body-forming members being counter parts of each other, and thus capable of being interchanged, if desired. The assembling members are formed with wire in the shape of a circle, and their terminals are united by being looped or hooked together,

as usual, although, if preferred, they may be lapped and soldered or brazed, and as this will be obvious detailed illustration thereof is deemed unnecessary. The terminal assembling members 1 and 3 have combined with them end-forming members 5, which are counterparts of the body members—that is, each is substantially a half-ring. The body and end members are combined with the assembling members by having their terminals looped around the same, as at 6, the end portions of the body and end members being alternately crossed and the loops 6 being alternately projected inward and outward relatively to the assembling members, whereby the connection between the body and end members and assembling members is rendered more stable. The body members are connected for hinged movement relatively to each other by metallic bands 7, each being provided at one end with a tongue 8 to engage a recess 9 in the other end and to be soldered therein when the band is secured around the member.

By the manner of combining the elements as herein described they will be positively held against accidental separation in use and will at the same time be free for pivotal movements relatively to each other, so that the adjustment of the device to produce different designs may readily and quickly be effected and the parts be maintained in the position to which they are shifted.

We claim—

1. A wire article embodying a plurality of assembling members, body members having their terminals pivotally connected with the assembling members, and means for connecting the intermediate portions of the body members, consisting of bands adapted to encircle the members, one end of each of the bands being provided with a tongue and the other end with a recess to receive the tongue.

2. A wire article embodying a plurality of assembling members, body members having their terminals pivotally connected with the assembling members, means for connecting the intermediate portions of the body mem-

bers, consisting of bands adapted to encircle the members, each band being provided at one end with a tongue and at the other end with a recess to receive the tongue, and end body members having their terminals pivotally connected with the outer assembling members and held out of contact with the like terminals of the body members.

In testimony that we claim the foregoing

as our own we have hereto affixed our signatures in the presence of two witnesses.

ALONZO ^{his} X HAYNES.
